UNITED STATES PATENT OFFICE.

CARL F. MAYER, OF CLEVELAND, OHIO, ASSIGNOR TO THE SWARTWOUT COMPANY, OF CLEVELAND, OHIO, A CORPORATION OF OHIO.

HEAT-INSULATING WALL.

Application filed June 27, 1921. Serial No. 430,536.

To all whom it may concern:

Be it known that I, CARL F. MAYER, a citizen of the United States, residing at Cleveland, in the county of Cuyahoga and State of Ohio, have invented a certain new and useful Improvement in Heat-Insulating Walls, of which the following is a full, clear, and exact description, reference being had to the accompanying drawings.

10 This invention relates generally to heat insulating walls, and more particularly to a sectional heat insulating wall that is especially suitable for use in various kinds of ovens such, for example, as core ovens; 15 enameling ovens; drying ovens, etc.

Heat insulating walls commonly used in constructions of the foregoing class are composed of inner and outer metallic plates that are separated by insulating material, 20 and the walls are usually made in sections to facilitate manufacture, transportation and handling; and to properly maintain the efficiency of the oven it is essential that the joints between the wall sections be of such 25 nature as will minimize the transmission of heat from the inner to the outer side of the wall.

The objects of my invention are to provide a sectional heat insulating wall that is 30 comparatively simple and inexpensive of construction and wherein the opposed edges of the wall sections or slabs are preferably substantially identical and so constructed as to avoid metallic continuity between the 35 inner and outer sides of the slab; to provide, with such a slab construction, means for connecting together the adjoining edges of adjacent slabs in such manner as to effectually preclude the passage of heat from the 40 inner to the outer side of the wall; to provide a joint of the immediately foregoing nature which permits of expansion and contraction of the connected slabs without affecting its efficiency and appearance; and to 45 provide a construction for oven wall sections or slabs through which assembling of the slab constituents is facilitated, and the disassembling thereof is rendered convenient, to the end that the insulation of the 50 wall slab may be easily inspected and replaced when occasion requires.

The objects above enumerated, and others

which shall hereinafter appear, are attained in the embodiment of the invention illustrated in the drawing accompanying and forming a part hereof and wherein Fig. 1 is a fragmentary perspective view of an oven wall, showing adjoining slabs or sections constructed and connected in accordance with my invention; and Fig. 2 is a sectional view showing adjoining slabs connected by a joint incorporating a modified form of finishing plate.

The wall slabs or sections A and B are substantially identical, and each comprises inner and outer metallic plates 1 and 2 that are properly spaced apart, and the space between these plates may be filled with a body 3 of insulating material, such as asbestos, the lateral edges of the body 3 terminating short of the corresponding edges of the plates 1 and 2, and edge strips 4 of channel formation are inserted between the projecting edge portions of the inner and outer plates with their side flanges 5 parallel therewith and insulated therefrom by strips 6 of suitable insulating material, such as asbestos. The flanges 5, and adjacent edge portions of the plates 1 and 2, have wrapped about them a second strip 7 of similar insulating material, and these parts are effectually clamped together between the inner and outer flanges 8 and 9 of metallic binders 10 that are U-shaped in cross section and, preferably, frictionally engaged with the above mentioned parts. To hold the binders against too easy a dislodgement, they and the plates 1 and 2 may be provided with cooperating retaining means, such as registering depressions 11, while the foregoing construction provides a substantial mechanical connection between the inner and outer plates 1 and 2, it affords an effectual insulation of the plates from each other. Furthermore, inasmuch as the binders 10 are frictionally engaged over the edge portions of said plates, and over the flanges 5 of the edge strips 4, with yieldable insulating material between them, the parts are firmly clamped together, although they may be conveniently separated by removing the binders 100 when it is desired to inspect or replace the body 3 of insulating material.

In assembling the wall, the slabs are ar-

ranged with their edges facing each other, and elements 15 of suitable insulating material are engaged within the channel shaped edge strips of opposed slabs so as to properly 5 align the slabs and hold them in correct relative position. In Fig. 1, I have shown finishing plates 16, having their lateral edges turned over and inwardly for cooperation with the edges of the outer flanges 9 of 10 binders 10, as applied to the binders to conceal the joint. The joint thus constructed effectually holds the adjoining slabs in a common plane, and permits a practical degree of expansion and contraction of the 15 slabs without in any way affecting the character or appearance of the joint.

With the form of finishing plate shown in Fig. 1, it is necessary to slip the plate endwise over the joint after the slabs are set up, 20 unless one of its edges is flanged inwardly after the other is applied, which is a more or less undesirable operation. In Fig. 2, I have shown a modified form of finishing plate 17 which may be applied to one slab 25 before the adjacent one is set up, obviating the need of feeding it endwise over the joint, thus making it more desirable of use under some circumstances.

Having thus described my invention, 30 what I claim is:

1. In a heat insulating slab, the combination of an inner and an outer metallic plate, a metallic edge strip disposed between the edge portions of said plates, means separate from said plates and edge strip for connecting them together, and means for insulating the foregoing elements from each other.

2. In a heat insulating slab, the combination of an inner and an outer metallic plate, a metallic edge strip disposed between the edge portions of said plates, means separable from the edge strip and plates for binding them together, and means insulating the foregoing elements from each other.

3. In a heat insulating slab, the combination of an inner and an outer metallic plate, a channel strip disposed between the edge portions of the plates with its side flanges substantially parallel to said portions, means insulating from each other the side flanges of the strip and the adjacent side portions of the plates, and further 55 means separate from said parts for connecting them together.

4. In a heat insulating slab, the combination of an inner and an outer metallic plate, a channel strip disposed between the edge portions of the plates with its side flanges substantially parallel to said edge portions, binders that are U-shaped in cross section engaged about said edge portions and flanges, and insulating material interposed between said flanges and edge por-

tions and between the last mentioned parts and the binders thereby to interrupt metallic continuity between the inner and outer sides of the slab.

5. In a heat insulating wall, the combination of a plurality of slabs arranged edge to edge, each slab comprising an inner and an outer metallic plate, a channel strip disposed between the edge portions of said plates and facing outwardly so as to be in opposed relation to the corresponding element of the adjacent slab, means binding together and insulating from each other the flanges of the channel strips and the adjacent edge portions of the plates, and an element comprised of insulating material occupying the opposed channel strips of adjacent slabs thereby to hold said slabs in a substantially common plane.

6. In a heat insulating wall, the combination of a plurality of slabs arranged edge to edge, each slab comprising an inner and an outer metallic plate, a channel strip disposed between the edge portions of said plates and facing outwardly so as to be in opposed relation to the corresponding element of the adjacent slab, binders that are U-shaped in cross section embracing the flanges of the channel strips and the adjacent edge portions of the aforesaid plates, insulating material interposed between said flanges and edge portions and between said parts and the binders, and an element comprised of insulating material occupying the opposed channel strips of adjacent slabs thereby to hold the said slabs in a substantially common plane.

7. In a heat insulating wall, the combination of a plurality of slabs arranged edge to edge, each slab comprising an inner and an outer metallic plate, a channel strip disposed between the edge portions of said plates and facing outwardly so as to be in opposed relation to the corresponding element of the adjacent slab, binders that are U-shaped in cross section embracing the flanges of the channel strips and the adjacent edge portions of the aforesaid plates, insulating material interposed between said flanges and edge portions and between said parts and the binders, an element comprised of insulating material occupying the opposed channel strips of adjacent slabs thereby to hold the said slabs in a substantially common plane, and finishing plates applied to and concealing the outer flanges of adjacent binders, the lateral edges of the finishing plates being turned inwardly and about the adjacent flanges of the binders.

8. In a heat insulating wall, the combination of a plurality of slabs arranged edge to edge, each slab permanently incorporating a flange along its edge that is opposed to the corresponding flange of the adjacent slab, and a finishing plate applied to and

concealing said flanges of adjacent slabs, the lateral edges of the finishing plate being turned inwardly and about said flanges.

9. In a heat insulating wall, the combination of a plurality of slabs arranged edge to edge, each slab having a flange along its edge opposed to and in substantially the plane of the flange of the adjacent slab,

and a finishing plate having its lateral edges turned over and inwardly upon its body portion then over and outwardly to form opposed channels for the reception of the aforesaid flanges of the wall slabs. ¹⁰

In testimony whereof, I hereunto affix my signature.

CARL F. MAYER.
